NEBULIZATION APPARATUS

Allan P. Bloxsom, Houston, Tex.

Application July 10, 1953, Serial No. 367,178

4 Claims. (Cl. 299—88.5)

The present invention relates to apparatus for nebulization.

In atomization, large droplets are produced at high speed. These large droplets impinge on the sensitive mucous membrane of the respiratory tract and produce coughing, gagging and other disagreeable sensations. Nebulization differs from atomization in that the large droplets are baffled out to a large extent, depending on the particular generator, and a fine fog or smoke is produced with particles that are non-irritating, and are practically insensible to the respiratory mucosa.

In aerosol therapy or administration, a consideration of particle size is essential. Particles 30 microns in diameter or larger are baffled out in the trachea and go no further; those of 10 to 30 microns in size reach the terminal bronchioles; those of 3 to 10 microns in size stop in the alveolar ducts; while those of 0.5 to 3 microns in diameter penetrate into the air sacs themselves.

The process of nebulization breaks the solution into millions of tiny particles in the range of 0.5 to 30 microns in size, thus enormously increasing the surface area of the solution. This, in turn, causes the particle to evaporate at an extremely rapid rate.

It has been demonstrated that nebulized particles of 10 microns and below completely evaporate within 0.02 second after production. An aqueous aerosol can be observed to disappear completely within about 3 to 6 inches of the mouth of the ordinary nebulizer. Therapeutically, this results in a relatively small amount of deposition on the respiratory mucosa beyond the pharynx and larynx. The reduced size of those particles that are deposited results in a slow coverage of the mucosa, since a great many of these tiny particles must be deposited before there is a sufficient number to coalesce and form a continuous film.

These difficulties have been overcome by adding the proper concentrations of glycerin and a detergent to the solution. The glycerin tends to hold onto the water in the droplet thereby inhibiting evaporation and stabilizing particle size. This results in a deeper penetration of the mist into the bronchial passageway. Glycerin alone, however, does not necessarily result in increased deposition, since the stabilized droplets tend to maintain their integrity and to rebound from obstructing surfaces. Recent data demonstrate that strong glycerin solutions may actually deposit to a lesser extent than plain aqueous solutions. An additional agent is required to lower the surface tension of the droplets so that they may become disrupted on contact with obstructing surfaces, that is, to make them "splatter out" rather than bounce off.

Detergents or wetting agents, in general, contain two radicals: (1) A lipophilic or hydrophobic group, and (2) a hydrophilic group. In an aqueous solution, the hydrophilic group is aligned on the surface next to the water; the hydrophobic group is directed upward toward the overlying gas. As a result, the surface has a film that is oil-like and has a much lower surface tension than water alone. Detergents possess the valuable qual-

2

ities of both lower surface and interfacial tension, of reducing viscosity, and of liquefying secretions. In addition, the lipophilic faction acts on fatty secretions in substances tending to dissolve them.

5 The aerosol technique consists in having the patients simply inhale a mist of the nebulized solution. This technique may be used for a number of uses, such as in neonatal atelectasis, prevention and treatment of hyaline membrane disease, bulbar poliomyelitis, pertussis, diphtheria, kerosene ingestion, irritating and chromatic conditions in which trouble from secretions is minimized, general anesthesia, bronchoscopy, tracheotomy, the treatment of inhalation of gases or dust and aspiration of foreign material, as well as other pulmonary conditions and prevention of respiratory obstructions.

Many difficulties attend the use of ordinary methods of prolonged aerosol administration. The nebulizers now in common use have a maximum capacity of only about 10 cc. of liquids so that an automatic and continuous 15 source of additional liquid is required. In some instances this has been achieved by inserting a needle through the side stopper of a nebulizer and dripping the therapeutic solution from a clysis bottle into the nebulizer through this needle. This method is simple and would be 20 ideal except that the fluid level is utterly impossible to control. No matter how carefully the rate of drip is measured, the nebulizer will either run dry or overflow, that is rain onto the patient in a short time thereby either failing to provide the continuous aerosol solution or thoroughly wetting the patient. In addition, it is obvious that such an apparatus is fragile and easily broken.

It is, therefore, a major object of the present invention to provide an apparatus for nebulization which will neither run dry nor overflow, that is rain onto the patient, and which provides a continuously-prolonged, trouble-free aerosol administration.

A further major object of the present invention is the provision of a nebulizer in which a constant fluid level is maintained at various rates of flow thereby providing a nebulizer capable of continuously-prolonged aerosol administration of substantially-uniform micron-particle size without running dry or overflowing onto the patient.

45 A further object of the present invention is the provision of a nebulizer which produces a nebulized smoke or fog principally made up of therapeutically-useful particles in the 0.5 to 3 micron range.

A further object of the present invention is the provision of a nebulizer in which the reservoir chamber is substantially sealed off from or connected to the turbulence chamber in such a manner so that frothing or "soaping up" does not occur when using a detergent.

Yet a further object of the present invention is the provision of a nebulizer of the above character which is simple and inexpensive to construct, shock resistant, requiring no adjustments, and reliable and dependable in use.

60 Other and further objects and advantages will be apparent from the following description of examples of the invention, given for the purpose of disclosure, taken in connection with the accompanying drawings, in which like character references designate like parts throughout the several views, and where

Figure 1 is a side elevation, partly in section, of a nebulizer constructed according to the invention,

65 Figures 2 and 3 are sectional views taken along the lines 2—2, and 3—3 of Figure 1,

Figure 4 is a side elevation, partly in section, illustrating a modification constructed according to the invention,

70 Figure 5 is a cross-sectional view taken along the line 5—5 of Figure 4,

Figure 6 is a fragmentary view, partly in section, of yet a further modification of the invention,

Figure 7 is a cross-sectional view taken along the line 7—7 of Figure 6,

Figure 8 is a fragmentary view, partly in section, illustrating a still further modification of the invention,

Figure 9 is a cross-sectional view taken along the line 9—9 of Figure 8, and

Figure 10 illustrates a screen or suitable filter used in connection with the apparatus of the invention.

Referring to the drawings, and particularly to Figures 1-3, a housing or casing 12 is provided which has what may be termed the primary reservoir 14 and a compartment 16 to house what may be termed the generator 18, the primary reservoir 14 and compartment 16 being separated by the partition 13. The housing 12 may be formed of any suitable material, and preferably is transparent and formed of a suitable nonbreakable material, such as plastic, in order to be shock resistant.

A closure member 19 is provided in the reservoir 14 so that the primary reservoir may be filled from time to time. The primary reservoir 14, obviously, may be made as large or as small as desired and should be airtight for satisfactory operation, as will be apparent later.

The generator 18 may be formed of any suitable material, such as glass, and may be suspended in the plastic case 12 so that the nebulizer may receive rough treatment without danger of breaking. The generator 18 may include at its lowermost portion what may be termed the secondary reservoir 20 which is in fluid communication through a narrow opening or neck 23 with a turbulence chamber 22, which in turn is in communication with a condensing chamber 24 for condensing larger micron particles so that they coalesce and drop into the secondary reservoir to be renebulized. Any suitable baffling means may be used, however, to baffle out the larger micron passages, such as providing a sharp or right-angle bend in the neck extending from the turbulence chamber, and any suitable means may be utilized to seal off the secondary reservoir 20 from the turbulent action in the turbulence chamber 22 to prevent frothing or "soaping up" when a detergent is used.

An inlet pipe or conduit to the nebulizer is provided and indicated by the reference numeral 26, to which may be threaded or otherwise secured the tubing or conduit 28 to a supply of solution for the aerosol of nebulized mist, not shown. Disposed at the upper end of the nebulizer and communicating with the condensing chamber 24 is the outlet pipe 30 to which is secured the plastic tubing or pipe 32 which carries the nebulized fog or mist to the enclosure surrounding the patient or to the patient to be administered in other ways, as desired.

Passing upwardly through the lower end of the secondary reservoir 20 and connected to the inlet pipe 26 is the upstanding tube 34 which is gradually tapered upwardly and terminates with a very small opening at its upper end. A second tube 36, open at its lower end and overturned at its upper end as at 38 is provided and secured to the upstanding tube 34. Thus, oxygen or air, or whatever fluid is being used, enters inlet tube 26 from the tube 28 and passes upwardly in the tube 34. The upper overturned end 38 is directly over the outlet of the tube 34 and a siphoning or venturi action is provided as gas flows out the upper end of the tube, drawing liquid from the second reservoir and saturating the gas.

As best seen in Figure 2, a tube or conduit 40 is provided which extends upwardly into the upper portion of the primary reservoir 14 and extends downwardly into the upper portion of the secondary reservoir 20. Similarly, a second pipe or tube 42 is provided which extends from the lower portion of the primary reservoir 14 to the lower portion of the secondary reservoir 20. Thus, the primary and secondary reservoirs 14 and 20, respectively, are in fluid communication with one another.

A screen or filter 44 may be provided in the tubing

42 delivering fluid to the secondary reservoir 20 to screen out impurities and the like, and as best seen in Figure 10, the screen 44 may comprise the housing 46 and screen element 48, the screen being connected to a cap member 50 so that it may readily be removed and cleaned as required.

In use, the primary reservoir 14 may be filled with a suitable liquid by removal of the closure member 19. In order to prevent all the liquid from running into the 10 generator 18, the case 12 is turned on its side to fill the reservoir 14. After stoppering with closure member 19, the case is then returned to the position illustrated in Figures 1 and 2 and pipe 26 connected to a suitable supply of gas, such as oxygen or air flowing in the pipe 28. 15 The outlet pipe 32 is inserted into a suitable enclosure or otherwise connected for desired use. As illustrated in Figure 1, the nebulizer is shown as secured to an incubator such as a Gordon-Armstrong incubator for aiding newborn infants in beginning their respirations to expand 20 more rapidly a greater number of alveoli, and a fragmentary portion of a wall 52 thereof is illustrated to which the nebulizer is secured by means of the bracket 54. It is understood, of course, that the nebulizer may be placed on or secured to a suitable support as desired and may 25 be used advantageously in all cases where an aerosol mist or fog is employed.

On turning the nebulizer to the position illustrated in Figures 1 and 2, the liquid in the primary reservoir 14 will flow downwardly through the pipe 42, the screen 44 and into the secondary reservoir 20 until the fluid level 30 L is reached, a vacuum in the primary reservoir 14 is then produced preventing the flow of any more liquid into the secondary reservoir 20. Thus, a constant liquid level L is provided.

35 As gas is flowed through pipe 28, inlet pipe 26 and the upstanding pipe 34 at the upper end thereof, the liquid is drawn upwardly from the secondary reservoir in the pipe 36 out the overturned end 38 because of the gas flowing beyond the open end 38. As illustrated in the 40 drawings, these openings are very small and the liquid is broken up into very small particles to produce a nebulized fog. The turbulence chamber 22 may be of a generally round or elliptical shape, viewed in cross section, and provides considerable turbulence of the gas and liquid thereby assuring a complete saturation of the air. The fog or mist passes upwardly from the turbulence chamber 22 into the condensing chamber 24, which also 45 is of generally rounded configuration, viewed in cross section, and which serves to baffle out larger micron particles so that they coalesce and drop downwardly through the turbulence chamber 22 into the secondary reservoir 20 to be renebulized. The nebulized fog or smoke then passes from the condensing chamber 24 upwardly in the outlet pipes 30 and 32 for the desired use.

50 The apparatus illustrated in Figures 1-3 is highly advantageous in that it produces a very high percentage of nebulization of particles of fluid in the 0.5 to 3 microns range which, as indicated heretofore, is small enough so that it passes and penetrates into the air sacs themselves.

55 Thus, in the embodiment illustrated in Figures 1-3, means are provided to maintain a substantially constant fluid level in the secondary reservoir irrespective of the rate of flow of the gas through the nebulizer inasmuch as the faster the rate of flow, the faster the secondary reservoir will be lowered thereby permitting air to enter the lower portion of the tube 40, which rises and passes into the upper portion of the primary reservoir 14 thereby relaxing the vacuum therein and permitting liquid to flow downwardly in the pipe 42 into the secondary reservoir. Thus, the liquid level may be adjusted by the position 60 of the lower end of the pipe 40 and a substantially constant liquid level is obtained at that point for all rates of flow of gas through the nebulizer. It is, therefore, apparent that prolonged and continuous aerosoled or nebu-

70 75

lized smoke or fog may be provided for any desired use without "running dry" or "raining" on the patient.

Figures 4 and 5 illustrate a modified means of providing a substantially constant fluid level in the secondary reservoir in that, essentially, the position of the primary reservoir and the connecting pipes between the primary and secondary reservoirs have been reversed. The arrangement is a gravity-type arrangement and performs satisfactorily.

Referring now to Figures 4 and 5, the primary reservoir 14a is positioned at the lower portion of case 12a, the generator 18a being positioned above the primary reservoir 14a. Here the pipe 42a may lead from the bottom of the primary reservoir and extends upwardly into the turbulence chamber 22a and has an overturned end 34 positioned above the upstanding pipe 34a and is connected thereto, as illustrated. In this example, the pipe 40a extends downwardly into the upper portion of the primary reservoir 14a and its upper end determines the liquid level.

Thus, as gas flows through the inlet tube 26a and out the upstanding tube 34a, the action of the gas flowing beyond the overturned end 43 of the tube 42a causes liquid to flow upwardly therein and be nebulized in the manner indicated in connection with Figures 1-3, inclusive. The larger particles coalesce and drop out, as indicated in connection with Figures 1-3, and drop back into the secondary reservoir 20a. When the liquid level L reaches the upper portion of the overflow pipe 40a, it overflows into the primary chamber 14a. Thus, a substantially constant liquid level is provided in this embodiment although, generally, the parts are reversed from that indicated in connection with Figures 1-3.

Also illustrated in the embodiment of Figures 4 and 5 is a second upstanding pipe 35 which is connected to the inlet pipe 26a similar to that of 34a and which has the pipe 37 secured thereto, as illustrated, the lower open end of which extends downwardly proximate the lower portion of the secondary reservoir 20a, and its upper overturned end 39 extends over the upper open end of the pipe 35. Thus, gas passing out the upper end of the pipe 35 causes a flow of liquid in the pipe 37 and is nebulized as indicated before.

It is understood, of course, that only a single pair of tubes or pipes is necessary in the embodiment of Figures 4 and 5; however, for the purpose of illustration, a plurality thereof is illustrated which is advantageous in providing large quantities of nebulized particles.

It is noted that in the examples of Figures 4 and 5, the liquid level L is above the restriction or neck 23a which is satisfactory if a detergent is not used. In the event a detergent is used, the upper portion of the outlet pipe 40a should be positioned below the neck or restriction 23a to prevent such frothing or soaping up.

In other respects, the embodiment of Figures 4 and 5 is similar to that of Figures 1-3, inclusive, and other than indicated, the operation of the two examples is the same.

A still further modification and example of the invention is illustrated in Figures 6 and 7, and with reference to these figures, a skirt portion 23 extends downwardly from the turbulence chamber 22b into the secondary reservoir 20b to a suitable point. In this illustration, the pipe 42b permits flow of liquid from a primary reservoir (not shown but such as illustrated in Figures 1 and 2) into the secondary reservoir 20b. The other parts are the same as that illustrated in connection with Figures 1-3.

In operation of the example of Figures 6 and 7, the liquid flows by gravity downwardly in pipe 42b into the secondary reservoir 20b from the primary reservoir in the same manner as indicated in connection with Figures 1 and 2. When the liquid level in the secondary reservoir 20b drops below the level of the lower part of the skirt 23, air will be permitted to flow from the interior of the turbulence chamber 22b and skirt 23 up in the

secondary reservoir 20b and up in pipe 42b to relieve the vacuum to permit additional liquid to flow downwardly from the primary reservoir in the tube 42b into the secondary reservoir 20b. Thus, a substantially constant liquid level is provided by the means illustrated and the other parts and operation of this example are similar to that described in connection with Figures 1-3.

Figures 8 and 9 illustrate yet a further example of the invention and illustrate the generator itself. This example is substantially the same as that illustrated in Figures 1-3; however, a single chamber 21 is provided for both the secondary reservoir and turbulence chamber. Thus, the walls connecting these two chambers are smoothly continuous; however, the upper portion of the chamber 21 has the upwardly-converging walls to provide a swirling or whirling action to create the necessary turbulence to substantially saturate the gas with small particles. In this embodiment, the tube 40c extends through the upper portion of the chamber 21 and downwardly to a point at which the liquid level is desired to be maintained, and the gravity feed pipe 42c extends downwardly through the upper portion of the chamber 21 into the lower portion thereof. This modification is advantageous where there is no frothing or soaping-up problems.

Other than the mentioned differences, the example of Figures 8 and 9 is the same as that of Figures 1-3 and the operation is the same.

It seems apparent that by maintaining a substantially constant fluid level in the secondary reservoir together with set openings of the nebulizing jets, constant predetermined percentages of nebulized particles will be produced at any constant rate of flow of gas through the nebulizer.

35 In view of the disclosure, it seems apparent that many and various changes in details and arrangements of parts will readily suggest themselves to those skilled in the art.

The present invention, therefore, is well suited to fulfill the objects set forth and attain the advantages incidental thereto as well as others inherent therein. The present invention, therefore, is to be limited only by the spirit of the invention and the scope of the appended claims.

45 What is claimed is:

1. A nebulizing apparatus comprising a substantially airtight primary reservoir, a secondary reservoir disposed below the primary reservoir, a first tube extending from the upper portion of the primary reservoir to the upper portion of the secondary reservoir and a second tube extending from the lower portion of the primary reservoir into the lower portion of the secondary reservoir whereby a constant liquid level is provided substantially at the lower portion of the first tube, a nebulizing tube extending 50 into the secondary reservoir and having its discharge end above the liquid level, a third tube tapering upwardly and having a small opening at its upper end proximate the discharge end of the nebulizing tube, the lower end of the third tube extending downwardly below the liquid level whereby gas passing out the discharge end of said nebulizing tube effects flow of liquid in said third tube and nebulization thereof, such flow of liquid lowering 55 momentarily the liquid level and thereby permitting gas to pass upwardly in said first tube into said primary reservoir and thereby permitting liquid to flow by gravity in said second tube downwardly into said secondary reservoir to bring said liquid level up to the lower portion of said first tube, inlet means connected to the nebulizing tube for flow of gas thereto, and outlet means connected to said secondary reservoir above the liquid level for flow of nebulized particles therefrom.

2. A nebulizing apparatus comprising a substantially airtight primary reservoir, a secondary reservoir disposed below the primary reservoir, a first tube extending from the primary reservoir to the upper portion of the secondary reservoir and a second tube extending from the

primary reservoir into the lower portion of the secondary reservoir whereby a constant liquid level is provided substantially at the lower portion of the first tube, a nebulizing tube extending into the secondary reservoir and having its discharge end above the liquid level, a third tube tapering upwardly and having a small opening at its upper end proximate the discharge end of the nebulizing tube, the lower end of the third tube extending downwardly below the liquid level whereby gas passing out the discharge end of said nebulizing tube effects flow of liquid in said third tube and nebulization thereof, such flow of liquid lowering momentarily the liquid level and thereby permitting gas to pass upwardly in said first tube into said primary reservoir and thereby permitting liquid to flow by gravity in said second tube downwardly into said secondary reservoir to bring said liquid level up to the lower portion of said first tube, inlet means connected to the nebulizing tube for flow of gas thereto, and outlet means connected to said secondary reservoir above the liquid level for flow of nebulized particles therefrom.

3. A nebulizing apparatus comprising a substantially airtight primary reservoir, a secondary reservoir disposed below the primary reservoir, a first tube extending from the primary reservoir to the upper portion of the secondary reservoir and a second tube extending from the primary reservoir into the lower portion of the secondary reservoir whereby a constant liquid level is provided substantially at the lower portion of the first tube, a turbulence chamber in fluid communication with and above the secondary reservoir, a nebulizing tube having its discharge end in the turbulence chamber, a third tube tapering upwardly and having a small opening at its upper end, the lower end of the third tube being positioned in the second reservoir and the small opening at its upper end positioned adjacent the discharge end of the nebulizing tube whereby gas passing through said nebulizing tube effects flow of liquid in said third tube and nebulization of said liquid, such flow of liquid lowering momentarily the liquid level and thereby permitting gas to pass upwardly in said first tube into said primary reservoir and thereby permitting liquid to flow by gravity in said second tube downwardly into said secondary reservoir to bring said liquid level up to the lower portion of said first tube,

5 inlet means connected to said nebulizing tube and outlet means communicating with said turbulence chamber whereby the gas may flow into the turbulence chamber through said nebulizing tube and nebulized particles may flow out of the turbulence chamber.

4. A nebulizing apparatus comprising a substantially airtight primary reservoir, a secondary reservoir disposed below the primary reservoir, a first tube extending from the primary reservoir to the upper portion of the secondary reservoir and a second tube extending from the primary reservoir into the lower portion of the secondary reservoir whereby a constant liquid level is provided substantially at the lower portion of the first tube, a turbulence chamber in fluid communication with and above the secondary reservoir, a condensing chamber in fluid communication with and above the turbulence chamber, a nebulizing tube extending into and having its discharge end in the turbulence chamber, a third tube tapering upwardly and having a small opening at its upper end adjacent the discharge end of the nebulizing tube, the lower end of the third tube positioned in said secondary reservoir whereby gas passing through said nebulizing tube effects flow of liquid in said third tube and nebulization thereof, such flow of liquid lowering momentarily the liquid level and thereby permitting gas to pass upwardly in said first tube into said primary reservoir and thereby permitting liquid to flow by gravity in said second tube downwardly into said secondary reservoir to bring said liquid level up to the lower portion of said first tube, inlet means connected to said nebulizing tube for flow of gas into the nebulizing tube, and outlet means connected to said condensing chamber for flow of condensed nebulized particles out of the condensing chamber.
